UNITED STATES PATENT OFFICE.

CLOISE H. BALDWIN, OF ERIE, KANSAS, ASSIGNOR OF ONE-HALF TO W. R. CLINE, OF ERIE,
KANSAS.

EXPLOSIVE-ENGINE.

No. 892,795.

Specification of Letters Patent.

Patented July 7, 1908.

Application filed October 25, 1906. Serial No. 340,604.

To all whom it may concern:

Be it known that I, CLOISE H. BALDWIN, a citizen of the United States, residing at Erie, in the county of Neosho and State of Kansas, have invented certain new and useful Improvements in Explosive-Engines, of which the following is a specification.

My invention relates to improvements in what may be termed explosive engines or 10 motors. Its object is to greatly simplify the construction of the parts and their arrangement, whereby may be obtained certain advantages in the running of the engine or motor and its driving power as will be appreciated later.

It consists of certain structural features or instrumentalities substantially as hereinafter fully disclosed and specifically pointed out by the claims.

20 In the accompanying drawing illustrating the preferred embodiment of my invention— Figure 1 is a sectional elevation thereof. Fig. 2 is an end view of the same. Fig. 3 is a side view, showing more particularly the piston together with its roller-bearing and springs. Fig. 4 is a plan view of the engine or motor, and Fig. 5 is a detached view showing more especially the piston-actuating cam. Fig. 6 is a longitudinal section of the piston 25 cylinder with its piston.

In the disclosure of my invention, I support in elevated position, in any suitable way by an upright frame *a*, or otherwise, the water-jacketed cylinder 1, having arranged 35 therein the usual piston 2, only one being employed herein and which has fixed to it parallel bars or arms 3, between which is hung or journaled a roller 4, having its periphery projecting beyond one end of said 40 cylinder. Said roller equipped or carrying arms 3 have fixed thereto a cross-rod 5 to which are suitably secured cross-head like members 5^a through which extend guide-rods 6 suitably fixed to a supplemental support 45 or frame *b*. Said guide-rods form supports for preferably helical or coiled springs 7 which are effective to exert pressure upon the cross-head like members 5^a and thus provide for maintaining effective contact or engagement between the roller 4 and the driving shaft cam presently described.

A driving shaft 8 is suitably journaled upon the supplemental bearing *b*, and in practice suitably equipped for transmitting 55 power or motion to the part to be operated

by the engine or motor, and which shaft has fixed thereto a cam 9 for its actuation by the piston 2 when under gas pressure, as will be readily appreciated. Said cam has two practically elliptical cam-surfaces or arms 60 10, 11 upon opposite sides of its axis, which is formed by the shaft 8, which arms, however, are of unequal length and which cam has also opposite concaved surfaces 12, 13 intermediately of said elliptical cam-surfaces 10, 11, the function of all of which will later appear.

In the head 14 of the cylinder 1 are arranged or applied as shown, the spring-seated inlet-valve 15, the spring-seated exhaust- 70 valve 16, and the electric igniter or plug 17, preferably of the "jump-spark" type, which are all well known in this art.

The ordinary centrifugal type of governor is suitably located and connected as shown 75 in the usual way with the engine or motor shaft, as well understood, for speed-control.

The operation is as follows: Assuming the parts to be in the position illustrated in Fig. 1, the longer cam 10 has forced the piston its 80 full outward stroke thus clearing the cylinder of all exhausted gases. The further rotation of the shaft 8 permits the piston to move inwardly thus sucking in an explosive charge. With the half completion of a revolution of 85 the shaft 8 the shorter cam 11 returns the piston part way on its outward stroke, thereby compressing the mixture between it and the head of the cylinder just prior to the explosion. The explosion now takes place and 90 has the effect of forcing the piston inward and imparting a new rotary impulse to the shaft, and with the return of the longer arm 10 of the cam, cylinder is again scavenged of 95 the exhaust gases, thus completing a complete cycle.

This invention is devised to be used as a motor using explosive products, such as gasoline, gas, alcohol, naphtha and all other products combined with air, forming an explosive mixture, in other words an explosive engine.

The piston actuating cam takes the place of the ordinary engine crank or shaft. The stroke of the short arm of the cam is about 105 two-thirds of the stroke of the longer arm or of such length that the arms of the cam with shorter throw is sufficient to allow for compression space; the longer arm of cam ejects 110 all of the previously burned charge.

The exhaust valve is placed in the cylinder head, in order to expel the greater per cent. of charge.

I claim:

5. 1. An explosive engine or motor as described, comprising a piston, an inlet-valve, an exhaust-valve, an igniter, a cam secured upon the engine-shaft and forming two arms of unequal length, adapted for co-action with 10 said piston, and means for automatically imparting the return stroke to said piston.
2. An explosive engine or motor as described, comprising a piston, equipped with a roller, an inlet-valve, an exhaust-valve, an igniter, a cam secured upon the engine-shaft and forming two arms of unequal length adapted for engagement with said roller, and means for automatically imparting the return stroke to said piston.
- 20 3. An explosive engine as described, comprising a piston having secured thereto parallel arms, a roller carried upon a cross-rod secured to said arms, an inlet-valve, an exhaust valve, an igniter, a cam fixed to the engine-shaft and formed of arms of unequal length adapted for engagement with said roller, and means for automatically imparting the return stroke to said piston.
- 25 4. An explosive engine as described, comprising a piston having secured thereto parallel arms, a roller carried by a cross-rod fixed

to said arms, cross-head like members also carried by said cross-rod springs for automatically imparting the return-stroke to said piston, means for carrying said springs, an inlet-valve, an exhaust-valve and an igniter for the piston chamber and means co-operating with the roller for moving the piston in one direction.

5. An explosive engine as described, comprising a piston having secured thereto parallel arms, a cross-rod secured to said arms, a roller carried by said cross-rod in a line intermediate of said arms, and an inlet-valve, an exhaust-valve and an igniter arranged in connection with the piston-chamber, a cam secured upon the engine-shaft and formed of two arms of unequal length, cross-head like members carried by said cross-rod, guide-rods fixed in position with relation to said 50 cross-head like members, and springs arranged upon said guide-rods and adapted to automatically impart the return stroke to said piston.

In testimony whereof I have signed my 55 name to this specification in the presence of two subscribing witnesses.

CLOISE H. BALDWIN.
